UNITED STATES PATENT OFFICE.

DAVID COLE, OF EL PASO, TEXAS, ASSIGNOR TO MINERALS SEPARATION NORTH AMERICAN CORPORATION, OF NEW YORK, N. Y., A CORPORATION OF MARYLAND.

APPARATUS FOR SEPARATING OR CONCENTRATING ORES.

1,351,096.

Specification of Letters Patent. Patented Aug. 31, 1920.

Original application filed August 3, 1915, Serial No. 43,444. Divided and this application filed December 4, 1915. Serial No. 64,993.

To all whom it may concern:

Be it known that I, DAVID COLE, a citizen of the United States, residing at El Paso, in the county of El Paso and State of Texas, have invented or discovered certain new and useful Improvements in Apparatus for Separating or Concentrating Ores, of which the following is a specification, reference being had thereto to the accompanying drawings.

This invention relates to the separation and concentration of ores and minerals by the flotation method wherein that part of the valuable portion which has been pulverized too fine to be readily concentrated by gravity separation, in water, is caused to be attached to bubble films and is carried over the top of the vessel or container in the froth which accumulates upon the surface 20 of the water and pulp when the mass is properly aerated; and wherein that part of the valuable portion not made fine enough to be lifted by the rising bubbles and be carried over by the froth as before mentioned, 25 will readily fall and may then be successfully and easily separated by the usual gravity system of concentration.

In the application of flotation methods two distinct divisions are recognized, in the older one of which violent agitation is created by the rapid revolution of stirrers or impellers, which has the effect of drawing air into the pulp and mixing it intimately with the mass. This method is expensive to 35 operate because it uses power inefficiently.

In the other division, which is known as the pneumatic method, air is introduced into the pulp through filtering mediums forming the flat horizontal, or inclined bottoms 40 of the tanks, and the process is embarrassed by the settling upon the porous mediums of sands and mineral grains too coarse to be held in suspension or moved far by the rising bubbles of air. Because it is essential 45 that the air be in very small bubbles in order to obtain efficient and satisfactory results in the separation of the minerals, and since small bubbles have little lifting power and do not cause violent agitation, it has 50 been found impossible in practical work entirely to prevent the clogging of the air filtering mediums except when all grains are of very small size. Forcing air under rela-

tively high pressure and in large volume through coarser, porous, filtering mediums 55 will prevent the lodging of particles and "blinding" of the filter, but the violent agitation of the mass undergoing treatment will then prevent the proper formation of froth and thus prevent the efficient degree 60 of separation of the minerals that is sought.

In the older machines before mentioned, depending upon mechanical agitation, it is necessary to move the material under treatment from one cell to another in a long 65 series of them for repeated treatment, in order to get an efficient result, and the passages between the different cells can only be successfully kept open and operated when the sands in the feed are exceedingly fine 70 and easily kept in suspension. Thus both divisions of the present best practice are limited so far as sizes of sands or ore are concerned to what is known as slimes or exceedingly fine sands, and neither of these 75 methods is adapted to the handling of relatively coarse unclassified material.

In the practice of ore concentration for the separation of minerals it is only necessary for the crushing operation to be carried far enough to liberate the valuable mineral crystals from their "gangue" or matrix so that they may be separated into different classes. Grinding to a point finer than this, (for the purpose of bringing the maximum 85 sized grains within the range of flotation treatment as above outlined) involves a much increased expenditure for crushing that would not otherwise be necessary.

In order to simplify the operations and 90 reduce the amount of expenditure by eliminating, to a maximum extent, the necessity of pulverizing the ore and minerals beyond the economical point previously explained, the efficient practice of the flotation method 95 of separating minerals involves, over the present state of the art, the successful and practical working out of the following desiderata:

First: Providing a grated air admission 100 filter or diaphragm, efficient for aerating purposes and affording ample passageways for the falling pulp and water so that velocities will be slow and no bubbles will be taken through the grates with the rejections. 105

Second: Providing an air admission me-

dium having the functions of the first item and whose air emitting surface is so arranged and disposed that material falling upon it will not be retained to clog the filtering surface or impede the free flow of air.

Third: Providing an air admission medium having the functions of the first and second items and which will allow the easy 10 passage of air outwardly into the pulp and water under treatment, but will allow the passage inwardly, under hydrostatic pressure, of clear water only, thus preventing the "blinding" of the air emission filter 15 from the deposition of solid matter on the inside of same.

Fourth: Providing a frothing machine of large capacity utilizing the filtering system mentioned in the foregoing items, into 20 which it will be possible to put the product made by the grinding machine, at relatively coarse sizes, directly and concurrently, without the introduction of intermediate screening, sizing, hydraulic or other classification, 25 to the end that the mineral values already fine enough for removal by flotation may be taken out first and as fast as produced by the grinding operation, thus making sure that the slimed minerals will be thoroughly 30 combed out of the pulp being treated before it is subjected to the gravity treatment which follows for the purpose of collecting and separating the coarser grains of "liberated" mineral too coarse to be amendable to 35 the frothing method of separation.

Fifth: Providing a frothing sizer of large capacity in which the stream of pulp undergoing flotation treatment will gravitate longitudinally through a succession of aerating 40 compartments in such a way that the heaviest and largest sand particles which fall fastest will be lodged in the first hopped subdivision of the tank, and successively smaller particles be deposited in the hoppers 45 arranged successively farther from the point of entry for the pulp under treatment.

Sixth: Providing a frothing machine of large capacity which will, concurrently with 50 the frothing operation, separate the portion which falls, into two or more classifications or sizes, so that one or more of the coarser sizes still containing grains of unliberated or "included" mineral may be returned to 55 the grinding machine to be further pulverized.

The present invention has for its general object the provision of an improved sizing classifier capable of fulfilling all of the foregoing conditions, and especially the fourth, 60 fifth, and sixth.

Other and more particular objects of the invention, together with means whereby the same may be carried into effect, will best be 65 understood from the following description

of one form or embodiment thereof illustrated in the accompanying drawings. It will be understood, however, that the particular construction described and shown has been chosen for illustrative purposes merely, and that the invention, as defined by the claims hereunto appended, may be embodied in other forms without departing from the spirit and scope thereof.

In said drawings:—

Figure 1 is a longitudinal vertical sectional view.

Fig. 2 is a transverse section on the line 2—2 of Fig. 1.

As shown the classifier or sizer comprises 80 a tank 14 having, at one end, an inlet 15 with which a trough or chute 13 communicates, and at the opposite end an outlet 16. 17 denotes a sliding gate arranged within the tank 14 adjacent the inlet 15 but spaced 85 from the latter, said gate being vertically adjustable in guides 18 by means of a hand wheel 19. The gate 17 serves to deflect downwardly the material entering at the inlet 15, and by adjusting said gate the effective height of said inlet may be controlled. 20 denotes a sliding gate adjacent the outlet 16 and adjustable in guides 21 by means of a hand wheel 22. By adjusting the gate 20 the effective height of the outlet, and consequently the normal level of the liquid in the tank 14, may be controlled. 23 and 24 denote baffle plates arranged adjacent the gate 20 for securing a gentle and even discharge of the liquid from said tank over 90 said gate into the outlet 16 and for preventing the discharge of froth at this point.

The bottom of the tank 14 is composed of a longitudinal series of hopper-shaped sizing compartments 25. Four of these compartments are shown in Fig. 1, although the precise number may be in accordance with the requirements. Coöperating with the compartment 25 at the end of the tank 14 adjacent the inlet 15 is an elevator operating in wells 56 within the sides of the tank, said elevator comprising a belt 27 carrying buckets 26 and passing over an idler pulley 28 and a supporting and actuating pulley 29. The pulley 29 is mounted on a shaft 30 110 suitably journaled above the tank 14 and adapted to be rotated from any suitable source of power by means of a belt pulley 31. Adjacent the pulley 29 the buckets 26 discharge their contents into a suitable chute 115 32. The remaining compartments 25, or those adjacent the outlet end of the tank, as shown, are provided with hydraulic or pneumatic lifts or ejectors 33 adapted to discharge material accumulating in said compartments into chutes 34 arranged at the 120 top of the tank and adapted to conduct said material to suitable concentrating tables (not shown) or elsewhere as may be desired.

The elevator 26, 27 and hydraulic or pneumatic lifts 33 are merely illustrative of convenient means for discharging the material accumulating in the compartments 25, and while such means are preferred it is obvious that said material might be otherwise discharged, as by providing said compartments with openings in their bottoms through which the material could be withdrawn into suitable chutes or other conveying means beneath the tank 14. Also while in the construction shown only one of the compartments 25 is arranged to discharge its contents into the chute 32, any suitable number of compartments at the inlet end of the tank may be so arranged, the essential idea being that the material from one or more of the compartments 25 at the inlet end of the tank be discharged separately, as into the chute 32, from the material in the remaining compartments at the outlet end of the tank which are discharged into chutes 34.

36 denotes launders arranged to receive material overflowing the top of the tank 14. As herein shown two of said launders are provided, one at each side of the tank within the same, each of said launders discharging through an opening 37 in the side of the tank midway of the length thereof, the material passing out from said openings being conveyed by troughs or other means (not shown) to any desired point.

Air is admitted to the tank 14 through a series of horizontally disposed filter or air tubes 35. Said tubes, in the construction shown, extend transversely of the tank and collectively constitute a tubular grating which extends substantially throughout the length of said tank so as to cover the entire horizontal cross sectional area thereof at a level above the sizing compartments 25. The tubes 35 are so constructed as to have a finely porous air emitting surface, whereby compressed air supplied to said tubes is discharged into the tank in a finely divided state and passes upwardly through the liquid in the tank in the form of numerous streams of fine bubbles.

The tubes 35 are closed at one end by caps 350 and, at their opposite ends, communicate with and are supported by headers 48 arranged at the opposite sides of the tank and supplied with compressed air from mains 50 through branch pipes 49 severally provided with valves 57. The headers 48 are preferably of less length than the tank 14, whereby the tubular grating, as a whole, is formed in sections arranged longitudinally of said tank, said sections corresponding in length substantially to the sizing compartments 25.

The pores of the tubes 35 are too small to allow solids to enter said tubes from the outside, under hydraulic pressure when the

compressed air is cut off, thereby preventing the internal clogging of said tubes. Said tubes are spaced from one another a sufficient distance to afford between them easy downward passages for the material under treatment into the sizing compartments 25, while being sufficiently close together to provide for the thorough aeration of the contents of the tank. By the provision whereby the material in the compartments 25 is removed therefrom at a point considerably below said tubes, all violent downward currents or vortices in the vicinity of said tubes, tending to draw the bubbles downwardly, are avoided, and all possibility of improper discharge of the finer material with the material properly deposited in the sizing compartments 25 reduced to a minimum. The air emitting surface of each tube 35 extends completely about the periphery or circumference thereof, so that all possibility of such accumulation of sediment as would clog the exterior of the tube and interfere with the proper discharge of air therefrom is prevented, it being obvious that, even though the entire upper surfaces of the tubes were covered by deposits, there would still be left a total unobstructed air emission surface equal to or greater than the entire horizontal area of the tank, notwithstanding the passages between the tubes.

At suitable points longitudinally of the tank 14 are provided vertically arranged shutters 52 extending across said tank and preferably spaced to correspond with the spacing of the sizing compartments 25. Said shutters are provided with slats 53 inclined downwardly in the direction of the flow through the tank and with adjustable flaps 54 connected to operating rods 55. The shutters 52 prevent currents from being set up longitudinally of the tank, racing one way at the bottom and the other at the top, the flaps 54 acting as valves to prevent the material from flowing in an improper direction, and, together with the inclined slats 53, directing the path of the current, causing it to plunge more or less in passing through the shutters, whereby the operation of the sizing compartments hereinafter explained may be varied or controlled. Also said shutters 52 tend to direct the upward passage of the bubbles from the air tubes, causing them to remain within that longitudinal portion of the tank in which they originated, so that the froth formed by said bubbles, as hereafter explained, will be richer above the first compartment than above the succeeding ones and may be separated from the other grades if desired.

The complete operation of the apparatus is as follows. The comminuted material from the mill, together with a suitable amount of water, and with or without cer-

tain other materials or frothing agents, such as oils, acids and the like, the whole forming what is known as "pulp," is discharged into the tank 14 through the inlet 15, the liquid filling said tank and overflowing into the outlet 16. The comminuted material above referred to, when the mill is operated in its most efficient and economical manner, as heretofore explained, includes, indiscriminately, finely pulverized ore including mineral particles or metallic sulfids, coarse lumps or oversize containing more or less unliberated mineral, and a considerable quantity of material of various intermediate sizes comprising grains of liberated mineral and gangue. The compressed air admitted through the tubular grating 35 passes upwardly through the tank in the form of numerous streams of fine bubbles, carrying with them the finest material, particularly the pulverized metallic sulfids, colloidal matter, and gels, and forming a froth column above the level of the liquid in the tank, the froth, together with the material carried thereby, overflowing at the top of the tank into the launders 36 and being suitably discharged through the openings 37. The bubbles also cause upward currents in the mass which resist the tendency of the rock particles to fall in response to gravity. As the pulp flows through the tank from the inlet to the outlet the coarsest particles and oversize will sink to the bottom of the tank first, and the successively smaller particles at successively later periods, so that said coarsest material and oversize will be retained in the sizing compartment nearest the inlet, and the successively smaller sizes in the other compartments, according to their size, practically nothing but muddy water passing out at the outlet 16. This grading or sizing of material may be controlled to a large extent by the adjustment of the gate 17 and of the shutter flaps 54, making the current plunge more or less at various points, and also by adjustment of the air pressure supplied to the several sections of the tubular grating by means of the valves 57. The coarsest material retained in the first sizing compartment 25 is removed therefrom by the elevator 26, 27 and discharged through the chute 32. The finest sulfid material discharged through the openings 37, as also the grains of intermediate sizes discharged

by the hydraulic lifts 33 and chutes 34 are severally and separately delivered at suitable points for such further treatment as may be applicable.

It will thus be seen that the apparatus above described is capable of receiving the ordinary run of the mill when run in its most economical manner, and without previous screening, that during the passage of the pulp through the apparatus the mineral values already fine enough for removal by flotation are immediately and constantly lifted out and discharged at suitable points, that the pulp is subsequently subjected to gravity separation or classification, that the several sizes thus graded are separately discharged from the apparatus, and that the oversize with its unliberated mineral values is further segregated from the other sizes and may be returned to the mill for re-grinding.

The air tube grating herein shown and described, and other parts of the apparatus which are limited in their utility to the frothing operation, are not claimed herein, being covered by the claims of a prior application filed by me August 3, 1915, Serial No. 43,444, of which this case is a division.

Having thus described my invention, I claim:

1. A hydraulic sizer comprising a tank having an inlet at one end, an outlet at the opposite end, and a plurality of sizing compartments at the bottom, said tank being constructed and arranged to permit a free flow of material therethrough in a substantially horizontal direction from said inlet to said outlet and above said compartments, and a series of vertically disposed spaced sets of shutters within said tank, said shutters having slats downwardly inclined in the direction of flow.

2. A hydraulic sizer comprising a tank having an inlet at one end, an outlet at the opposite end, and a plurality of sizing compartments at the bottom, said tank being constructed and arranged to permit a free flow of material therethrough in a substantially horizontal direction from said inlet to said outlet and above said compartments, and a series of vertically disposed sets of shutters within said tank spaced to correspond with said compartments.

In testimony whereof I affix my signature.
DAVID COLE.
